WILLIAM SCHAAKE, OF PITTSBURGH, PENNSYLVANIA, ASSIGNOR TO WESTINGHOUSE ELECTRIC & MANUFACTURING COMPANY, A CORPORATION OF PENNSYLVANIA

CONDUCTOR SUPPORT

Application filed November 6, 1928. Serial No. 317,538.

My invention relates generally to supporting devices for trolley conductors and more particularly to adjustable inclined hangers for supporting conductor clamps permanently in vertical positions.

When the catenary principle is employed in the construction of trolley-conductor system, wherein the conductor is suspended from a messenger cable, provision must be made to support the trolley-conductor on the curved portions of the system in such manner as to cause it to assume a curved path even though the messenger-cable extends in straight lines between predetermined suspension points. Furthermore, it is desirable to support the conductor clamps in such manner as to retain them in vertical positions, regardless of the inclination of the supporting rods which are attached to the messenger cable, in order that the operation of the trolley or current collector shall not be interfered with in any way.

The object of my invention is to provide a conductor support which shall be of simple construction, economical to manufacture and easily installed and adjusted to the desired working position.

A more specific object of my invention is to provide for supporting a trolley-conductor clamp and retaining the clamp in a vertical position, regardless of the angular relation between it and the supporting rod.

A further object of my invention is to provide, in a conductor support, a pivotal connection between the supporting rod and the conductor clamp which shall be adjustable to control the relative angular relations of the rod and the clamp.

Other objects of my invention will become evident from the following description, taken in conjunction with the drawing, in which:

Figure 1 is a side view of a conductor support embodying the features of my invention, showing a single current conductor supported from a messenger cable;

Fig. 2 is an end view of the conductor support shown in Fig. 1, showing details of construction;

Figs. 3 and 4 are side and end views, respectively, of a double conductor clamp em-

bodying the same features of construction as those shown in Figs. 1 and 2.

Referring now to the drawing, 1 designates generally a conductor clamp comprising a plurality of clamp members 2 and 3. In order to provide for securely holding a trolley conductor 4, the lower edges of the clamp members are provided with jaws 5 and 6 which, according to the usual practice are shaped to conform to the shape of the trolley conductor and extend throughout the length of the clamp members.

It will be observed that Figs. 1 and 2 show a particular form of clamp suitable for supporting only a single conductor, while that shown in Figs. 3 and 4 is provided with auxiliary jaws 7 and 8 on the upper edges of the clamp members by means of which a second conductor may be supported in close parallel relation to the lower conductor which is engaged by the collector device. Since the same features of my invention are found in both forms of clamps which are shown, only that shown in Figs. 1 and 2 will be referred to in the detailed description.

The conductor clamp 1 may be supported from a messenger cable 9 by any suitable means. In this embodiment of the invention, a supporting-rod 10, having a hook portion 11 for engaging the messenger-cable 9, is provided.

In order to secure the clamp members 2 and 3 to the trolley conductor 4, they are provided with registering transverse holes to receive a tie-bolt 12, as shown. In this particular embodiment of the invention, the bolt 12 is threaded at one end to engage the internally threaded portion of the clamping member 2. It will readily be understood that this construction permits the drawing of the clamp members 2 and 3, tightly together by means of a nut 13. Furthermore, by being in threaded engagement with the back clamp member 2, the bolt 12 is easily adjusted to change its transverse position with respect to the clamps and thereby perform a function which will be referred to in detail hereinafter.

It will readily be understood that it is highly desirable to maintain the clamp 1 in a ver-

tical position, regardless of the inclination of the supporting rod 10 and still provide flexibility in the adjustment of the angular relation between the supporting rod 10 and the clamp 1. With a view towards this purpose, means, comprising a clevis 14 having integral cam members 15 and 16, is provided for connecting the clamp 1 and supporting rod 10 together in a flexible and adjustable manner.

10 Since the clamp 1 must be pivotally connected to the supporting rod 10, the tie-bolt 12 is provided with an eye portion 17 which may be connected to the clevis 14 by means of a pin 18.

15 As shown, the clevis 14 is of fork shape, having portions extending on the sides of the bolt 12 to form the cam members 15 and 16. The cam members 15 and 16 are disposed to engage the flat side portion of the clamp member 2 and, thereby, determine the angular relation between the clamp member 1 and the supporting rod 10. Since the distance between the side of the clamp member 2 and the pivotal connection between the bolt 12 and clevis 14 may be varied by screwing the bolt inwardly or outwardly, it is evident that the cam members 15 and 16 may be caused to engage the clamp member 2 in whatever position may be desired.

20 It will be observed that the shape of the cam members 15 and 16 is such as to effect a wedging action between them and the side of the clamp member 2 with which they are in engagement when a strain is exerted upon the clamp due to the weight of the trolley conductor which tends to decrease the angle between the clamp and the supporting rod. However, in order to permit a slight upward movement of the clamp 1, due to the force exerted by a passing trolley or current collector, the cam members 15 and 16 are so shaped as to relieve the pressure between their bearing surfaces and the side of the clamp when the conductor and clamp are moved upwardly. 25 It will readily be understood that this feature provides for a flexible connection between the conductor and the messenger cable 9 which tends to relieve the strains in both the conductor and conductor support and, at the same time, maintains the conductor clamp in the desired vertical position.

30 It is evident that a conductor-support embodying the features of my invention is easily installed and readily adjusted. After the clamping members 2 and 3 have been secured, in proper position, to the trolley conductor 4 by means of the bolt 12, the supporting rod 10 may be adjusted to the desired angular position with respect to the clamp, by screwing the bolt 12 inwardly or outwardly.

35 Since, in the preferred embodiment of my invention which is shown in Figs. 1 and 2, the same bolt is utilized for adjusting the cam members as for securing the clamp members together, it is evident that a very sim-

ple and economical form of construction has been provided. However, in the case of a double-conductor clamp, such as is shown in Figs. 3 and 4, it may be advisable to provide separate bolts for securing the clamp members together, thereby utilizing the main bolt solely for adjusting the cams.

40 It may be stated in conclusion that, while the illustrated example constitutes a practical embodiment of my invention, I do not wish to limit myself strictly to the exact details herein illustrated, since modifications of the same may be made without departing from the spirit of the invention as defined in the appended claims.

45 I claim as my invention:

1. A hanger for trolley conductors comprising, in combination, a clamp for engaging a trolley conductor, a bolt extending through the clamp, a supporting rod pivotally connected to the bolt, and means on the end of the supporting rod to engage the side of the clamp, whereby the relative angular positions of the clamp and supporting rod may be varied by adjusting the bolt.

50 2. A hanger for trolley conductors comprising, in combination, a clamp for engaging a trolley conductor, a bolt extending through the clamp, a supporting rod pivotally connected to the bolt, and means on the end of the supporting rod to engage one side of the clamp to maintain a predetermined angular relation between the supporting rod and clamp, whereby said clamp is caused to set in a perpendicular position under all angular relations between it and the supporting rod.

55 3. A hanger for trolley conductors comprising, in combination, a clamp for engaging a trolley conductor, an eye bolt extending through the clamp, a supporting rod pivotally connected to the eye bolt, a cam provided on the end of the supporting member, said clamp having a face disposed to be engaged by the cam, said eye bolt being adjustable to move the cam relative to the clamp face to change the relative angular relations of the clamp and the supporting member.

60 4. A hanger for trolley conductors comprising, in combination, a clamp for engaging a trolley conductor, a rod for supporting the conductor clamp from a point laterally displaced from the vertical plane containing the conductor, a cam member secured to the end of the supporting rod and an eye bolt extending through the clamp and connected in pivotal relation to the cam member, said eye bolt being adjustable to actuate the cam member into engagement with the clamp member to vary the relative angular relations of the clamp and the supporting rod.

65 5. A hanger for trolley conductors comprising, in combination, a messenger cable, clamp jaws for engaging the conductor, an eye bolt extending through the clamp jaws,

a supporting rod for suspending the clamp jaws and conductor from the messenger cable, means for pivotally connecting the supporting rod to the eye bolt, a cam on said connecting means, said clamp jaws having flat face portions to engage the cam, said eye bolt being adjustable to vary the distance between the pivotal connection and the flat face portion of the jaw to determine the point of engagement between the cam and said face portion, thereby to change the angular relation of the jaws and supporting member.

6. A hanger for trolley conductors comprising, in combination, a messenger cable, 15 clamp jaws for engaging the conductor, an eye bolt extending through the clamp jaws, a supporting rod for suspending the clamp jaws and the conductor from the messenger cable, means for pivotally connecting the supporting rod to the eye bolt, a cam on said connecting means, said clamp jaws having flat face portions to engage the cam, said eye bolt being in threaded engagement with one of said clamp jaws to retain the cam in a fixed 25 predetermined engaging position relative to the side of the clamp jaw.

7. A hanger for trolley conductors comprising, in combination, a clamp for engaging a trolley conductor, an eye bolt extending 30 through the clamp, said eye bolt being in threaded engagement with the clamp, a suspension member provided with a clevis secured to the eye bolt to permit relative movements of the clamp and suspension member 35 in one plane, a cam on the clevis disposed to engage the side of the clamp, thereby to retain the clamp and suspension member in predetermined angular positions relative to one another during vertical movements of the clamp and the conductor.

40 8. A hanger for trolley conductors comprising, in combination, a clamp for engaging a trolley conductor, an eye bolt extending through the clamp, a supporting rod for the clamp, a clevis for connecting the supporting rod to the eye bolt, said clevis being provided with a cam member disposed to engage one side of the clamp, said eye bolt being adjustable transversely to actuate the cam into 45 engagement with the clamp, thereby to vary the angular relation between the clamp and the supporting rod.

50 9. A hanger for trolley conductors comprising, in combination, a clamp for engaging a trolley conductor, an eye bolt extending through the clamp, a supporting rod for the clamp, a clevis for pivotally connecting the supporting rod and the clamp, said clevis 55 being provided with forked portions at the sides of the eye bolt, the forked portions comprising cam members disposed to engage the side of the clamp, said eye bolt being adjustable to control the position of the cams 60 with respect to the clamp and thereby the

angular relationship between the clamp and the supporting rod.

In testimony whereof, I have hereunto subscribed my name this 26th day of October, 1928.
